UNITED STATES PATENT OFFICE.

WILLIAM DUFFIELD ROBINSON, OF PHILADELPHIA, PENNSYLVANIA.

MAGAZINE-CAMERA.

SPECIFICATION forming part of Letters Patent No. 619,695, dated February 14, 1899.

Application filed November 1, 1897. Serial No. 657,032. (No model.)

To all whom it may concern:

Be it known that I, WILLIAM DUFFIELD ROBINSON, of Philadelphia, in the State of Pennsylvania, have invented certain new and useful Improvements in Cameras, whereof the following is a specification, reference being had to the accompanying drawings.

My invention relates to magazine-cameras adapted to contain a number of sensitized plates in two series or packs and comprising shifting mechanism operative by means of an exterior handle, whereby single plates may be simultaneously shifted from each of said series or packs to the other.

My invention comprises, first, plate-shifting mechanism of said type simple in construction and so disposed in the walls of the camera-box that the latter may be made of minimum dimensions; second, a pile-covered roller which serves to prevent the ingress of light to the plate-magazine and facilitates the shifting of said plates in light-tight contact therewith; third, a peculiar form of plate-holder, and other details of construction hereinafter set forth.

In the drawings, Figure 1 is a side elevation of a camera, showing a convenient embodiment of my invention. Fig. 2 is a rear elevation of the camera shown in Fig. 1 with its rear door removed. Fig. 3 shows a central vertical section on the line 3 3 of Fig. 2. Fig. 4 shows a plan section on the line 4 4 of Figs. 2 and 3. Fig. 5 is a perspective view showing certain details of construction of the shifting mechanism. Fig. 6 is a perspective view of one of the plate-holders shown in section in Fig. 3.

In said figures, A is the camera-box, provided with the focusing-tube B, which carries the lens C and is longitudinally adjustable in any convenient manner within the focusing-chamber B^X. Behind said focusing-chamber is the magazine-chamber D, adapted to contain a series of sensitive plates X in a pack in line with said lens C and a second series of sensitive plates X' in a pack disposed above the first pack X. Each of said sensitive plates is conveniently mounted face outward in an open frame or holder X, hereinafter described.

The rear wall of the chamber D and the camera-box A is formed as a removable door

E, provided with suitable slide-latches e, which serve to retain it normally in the position shown in Fig. 3 by engagement under 55 the keeper-plates e', secured upon the box A.

To maintain the sensitive plate-holders x in proper relation with the shifting mechanism, it is desirable to provide the respective packs X and X' with springs F and F', the 60 former being secured at its end f upon the door E and serving to thrust the pack X forward, and the latter being secured at its end f' upon the partition A' in the camera-box A and serving to thrust the pack X' rearward. 65

Extending between the two compartments of the chamber D is a horizontal shaft G, provided with an exterior operating-handle G^X. Upon said shaft G are fixed gear-wheels H H, respectively, existing within the opposite side 70 walls A² A² of the camera-box.

Vertical channels A³ A³ and A⁴ A⁴ are provided in the side walls A² as slideways for the racks I I and J J. Said racks are supported in the side walls A² A² behind the 75 plates a² a², secured, respectively, upon the inner faces of said side walls. Said face-plates a² a² are provided with inwardly-projecting ribs a³ a³, which maintain the packs X and X' in the respective compartments of 80 the chamber D and serve as bearings for the shaft G.

The opposed racks I I are coupled by means of a plate-shifting bar I^X, pivotally mounted in the bearings i i in the upper extremities of 85 said racks. The opposed racks J J are similarly coupled by means of a plate-shifting bar J^X, pivotally mounted in bearings j j in the lower extremities of said racks. The respective pairs of coupled racks I and J are so 90 mounted in engagement with the gear-wheels H H that rotation of the latter serves to shift the bars I^X and J^X vertically in parallelism. The normal position of the racks and shifting-bars is shown in Figs. 1 and 3. In said 95 position the racks and bars are at the outer extremities of the respective channels A³ and A⁴, a single plate of the pack X in its holder x being in line with the bar J^X and a single plate of the pack X' in its holder x being in 100 line with the bar I^X.

The parts just described are retained in normal position by the detent-plate K, conveniently mounted upon the exterior of the

camera-box A in position to engage the actuating-lever G^x and prevent its rotation in the direction indicated by the arrow in Fig. 1.

The plate-holders x are preferably made of 5 sheet metal and, as shown in Fig. 6, comprise a flat back x' , provided with forwardly-extending overhanging flanges $x^2 x^3$ at their opposite sides. The bottom flange x^3 does not overhang the plate, but is returned upon 10 itself, as shown in Fig. 3, thus serving as a stiffening-rib to maintain the back x' in plane. In operation the sensitized plates rest upon the lower flange x^3 and are thrust forward in 15 contact with the overhanging side flanges x^2 by flat springs $x^4 x^5$, the latter being riveted at one extremity to the back x' , as indicated at Fig. 6. In the normal operation of the device all of the said holders x are filled with 20 sensitized plates and placed in the chamber D, as shown in Fig. 3. Said plates are then successively exposed at the front of the pack X, behind the lens C, and lifted thence to the pack X' , as follows: The exterior operating-lever G^x is sprung outwardly from engagement 25 with the detent-plate K and the shaft G and the gear-wheels H rotated in the direction of the arrow upon Fig. 1. The resulting vertical movement of the bars J^x and I^x serves to simultaneously shift the forward plate X 30 and the rearward plate X' , respectively, upward and downward, each into the other pack. Reverse movement of the operating-handle G^x serves to return the bars I^x and J^x to their normal position. In order that said return 35 movement of the bars may be effected, it is essential to provide means to temporarily retain the holders x out of the path of travel of the bars I^x and J^x against the action of the respective springs F and F'. To effect this 40 end the bars I^x and J^x are provided with lugs i^x and j^x , which overlap the inner edges of the packs X and X' when the bars are in their inward position. In said position the outer edges of the packs are retained by the vertical 45 knife-edged flanges l and m of the springs L and M, which, however, are normally disengaged, as shown in Fig. 3, by means of their horizontal lugs l' and m' , which extend in the path of travel of said bars. It is obvious that 50 said mechanism may be used to shift said plates into any desired relation in the camera-box without exposure, so that when desired certain plates may be presented to the rear side of the box in convenient position for removal through the opening covered by the door E. To facilitate such manipulation of the plates, I prefer to provide a telltale or counter N upon the camera-box A, as indicated in Fig. 1. Said counter comprises a 55 toothed disk n , adapted to be engaged and shifted by the pivoted pawl n' when the shaft G is rotated in the direction of the arrow upon Fig. 1. In the reverse movement of said shaft and pawl the latter rides idly over the toothed disk n , rotation of the latter in reverse direction being prevented by the keeper-spring n^2 .

To prevent access of light from the focusing-chamber B^x to the magazine-chamber D at the top of the forward plate X, I provide 70 a roller O, covered with pile fabric o and mounted for rotation in the face-plates $a^2 a^2$. The pile of said fabric serves to exclude the light at the aforesaid junction, and the roller O serves to facilitate the vertical movement 75 of the plates X.

As indicated in Fig. 3, the space forward of the chamber D in the upper part of the camera-box may be utilized to contain a 80 finder A x .

I am aware that it is not broadly new to shift plates in a magazine-camera by means of racks actuated by gear-wheels. I therefore do not desire to broadly claim such construction. I believe it to be new, however, 85 to combine racks and gear-wheels of the character described with the described form of shifting-bars, &c. I therefore do not desire to limit myself to the precise construction which I have shown and described. 90

I claim—

1. In a camera, the combination with a magazine-chamber provided with means for supporting two packs of plates, of mechanism for simultaneously shifting one plate from each 95 pack to the other pack, said mechanism comprising a rock-shaft, a gear-wheel upon said rock-shaft, racks in mesh with said gear-wheel, and plate-shifting bars, pivotally journaled in the outer extremities of said racks substantially as and for the purpose set forth. 100

2. In a camera, the combination with a magazine-chamber provided with means for supporting two packs of plates, of mechanism for simultaneously shifting one plate from each 105 pack to the other pack, said mechanism comprising a rock-shaft, two gear-wheels upon said rock-shaft, respectively existing at opposite sides of said magazine-chamber, two racks in mesh with each of said gear-wheels, 110 and two plate-shifting bars each pivotally journaled in two of said racks at their outer extremities, and extending transversely from side to side of said magazine-chamber, substantially as and for the purpose set forth. 115

3. In a camera, the combination with a magazine-chamber, provided with means for supporting two packs of plates, of mechanism for simultaneously shifting one plate from each pack to the other pack, said mechanism comprising a rock-shaft, a gear-wheel upon 120 said rock-shaft, racks in mesh with said gear-wheel, pivoted plate-shifting bars journaled in the outer extremities of said racks, and pack-retaining lugs upon said bars, substantially as and for the purpose set forth. 125

4. In a camera, the combination with a magazine-chamber provided with means for supporting two packs of plates, of mechanism for simultaneously shifting one plate from each pack to the other pack, said mechanism comprising a rock-shaft, a gear-wheel upon 130 said rock-shaft, racks in mesh with said gear-wheel, plate-shifting bars secured to the outer

extremities of said racks, and extending from side to side of said magazine-chamber, pack-retaining mechanism comprising knife-edged vertical flanges, and horizontal flanges to engage said bars, substantially as and for the purpose set forth.

5. In a camera the combination with members adapted for relative movement, of means to prevent the passage of light between said members, comprising a roller mounted for ro-

tation upon one of said members, and a pile covering for said roller adapted to contact with the other of said members, and rotate in light-tight contact therewith, substantially as and for the purpose set forth.

WM. DUFFIELD ROBINSON.
